DOMESTIC RANGE

Carl W. Tilus, Washington Township, Ohio, assignor to Westinghouse Electric Corporation, Pittsburgh, Pa., a corporation of Pennsylvania

Filed Jan. 27, 1964, Ser. No. 340,210

2 Claims. (Cl. 219—392)

This invention relates to domestic ranges and particularly to a domestic range wherein the surface heating units are mounted on a horizontally slidable platform.

One of the more popular types of domestic range on the market today provides for mounting the surface units on a slidable platform permitting the units to be enclosed, or partially enclosed, in the cabinet when not in use. This arrangement is generally found in combination with an oven located substantially at "eye level" to provide convenient access to the oven enclosure. With the oven located as described, and the surface unit disposed at a convenient height, there is generally a space between the bottom of the oven and the surface units when in the stored position. This space has heretofore been used primarily for storage of kitchen utensils of a shelf, or shelves, provided for such purpose.

It is an object of the present invention to better utilize the space above the surface units in the stored position, by providing a warming shelf which is useful in maintaining cooked dishes at a proper serving temperature, as well as for warming pastries and other foods where it is desirable to warm without cooking.

Another object of the invention is to provide a warming shelf for a domestic range of the type described, which shelf is heated by the range surface units.

A further object of the invention is to provide a warming shelf which is simple in construction, easy to manufacture, and readily adaptable to domestic ranges of the type described.

These objects of the invention, and other objects which will become apparent as the description proceeds, are achieved by providing a novel shelf structure disposed above the range platform together with means to transfer heat energy from a surface unit located on the platform to the area adjacent the shelf member when the surface units are in the stored position. In addition, a thermostatic element is provided in the warming area and so located in the control circuit of the surface unit 23 to provide for controlling the temperature of the surface unit during the warming process.

For a better understanding of the invention reference should be had to the accompanying drawings, wherein:

FIGURE 1 is a front perspective view showing a combination range and oven having the invention employed therein;

FIG. 2 is a side elevational view showing the range structure of FIG. 1, and having a portion of the structure broken away for clarity;

FIG. 3 is a top sectional view taken along the line III—III of FIG. 2, showing details of the invention;

FIG. 4 is a side elevational view taken along the line IV—IV of FIG. 3, showing in detail a mechanism employed in the range structure;

FIG. 5 is a side elevational view similar to FIG. 4 showing the mechanism of FIG. 4 in the operated position;

FIG. 6 is a schematic electrical diagram showing a circuit employed in the invention; and

FIG. 7 is a schematic electrical diagram showing an alternate circuit which may be employed in the invention.

While the invention has been shown as illustrated in a range and oven combination, and will be so described, the principles of the invention are broadly applicable to

countertop ranges of the platform type which are movable from a cooking position, wherein the surface units are exposed, to a storage position within a cabinet.

Referring to the drawings, especially FIG. 1, there is shown a range oven combination 10 having wall structure including a horizontal shelf member 11. The wall structure of the range 10 further includes a pair of side walls 12 and 13, and a rear wall 14, which abuts the shelf member 11 and serves to support the member on three sides. In the embodiment shown, the lower portion of the oven provides a top wall 16, and a pair of glass closure members 17 and 18 are provided between, and slidably supported by, the top wall and the shelf member 11 to provide a heating oven enclosure above the shelf 11.

As best seen in FIGS. 1 and 2, a platform member 19 is slidably supported below the shelf member 11 and is movable from a first or extreme rear position, as shown in FIG. 2 to a second extreme forward position as shown in FIG. 1. The slidable platform member 19 has a horizontal top surface 21 which is provided with a plurality of surface heating units including rear units 22 and 23. It will be noted that with the slidable member 19 disposed as shown in FIG. 1, in the extreme forward position, the surface units are exposed for the heating of pans, skillets or other kitchen utensils. In the position shown in FIG. 2, the rear surface units 22 and 23 are disposed beneath the horizontal shelf member 11 and are in a stored position.

In a domestic range unit of the type mentioned, it is often desirable to provide a safety means for preventing the units being placed in a stored position while the controls remain in the "on" position. In the present embodiment, such a device is best shown in FIGS. 3—5. A safety switch 24 is mounted at the forward part of structural side wall 13 and has a plunger 26 which is actuated by rotation of a pivotal member 27 also mounted to side wall 13. A tab 28 is disposed on the slidable platform 19 and positioned to contact the pivotal member 27 when the platform 19 is disposed in the extreme forward position as shown in FIGS. 1 and 5. With the platform 19 located in a position other than the extreme forward position, the plunger 26 remains extended as shown in FIG. 4, and the circuit to the two rear surface unit switches remains open. With the platform member 19 in the extreme forward position, as shown in FIG. 5, the plunger is actuated and the circuit to the rear surface units is closed as is best shown in FIG. 6, and described in the following paragraphs.

As shown in FIG. 2 and FIG. 3, the shelf member 11 and adjacent structure are of a novel construction to provide for heating articles placed on the shelf. The shelf member 11 comprises an upper sheet 29 and a bottom sheet 31 having a pair of rectangular plates 32 and 33 disposed therebetween. The bottom sheet 31 has a plurality of holes 34 located near its periphery and adjacent the plates 32 and 33. A row of holes 36 is provided adjacent the forward edge of the top sheet 29 and provides communication between the space beneath the top sheet and the enclosure directly above the shelf member 11. With the surface units 22 and 23 located beneath the shelf 11, the aforementioned structure provides heat transfer means for heat produced by the surface units. Heat energy from the surface unit 22 or 23 is transferred to the top of the shelf 11 through the openings 34 in the sheet 31 and through the holes 36 in the sheet 29 by convection, and by conduction through the rectangular plates 32 and 33, which are manufactured of a material having high heat conductivity, for example, an aluminum or steel alloy.

In addition to the above-described heat transfer means, slotted openings 37 are provided below the surface 21

at the rear of the slidable platform member 19 for escape-
ment of heat from the interior of the platform. A rear-
wardly dished portion 38 of the rear wall 14 extends
downward, and adjacent the openings 37, to provide a
passage for heat of convection to a plurality of slotted
openings 39 provided in the wall 14. A cycling thermo-
stat 41 is disposed adjacent the dished portion 38 of the
wall 14 and in heat transfer relation therewith to re-
spond to the temperature of the air adjacent the shelf
member 11. The thermostat 41 is set for cycling the
electrical energy to the surface unit 22 or 23 at a pre-
determined temperature to provide adequate heating of
the air above shelf 11, and is located in the electrical
circuit as best shown in FIG. 6.

Referring now to FIG. 6, there is shown a schematic
electrical diagram used with the present invention, hav-
ing portions and details omitted where are not essential
to a full understanding of the invention. The rear surface
units 22 and 23 are connected to a standard 236
volt power source through a suitable control device in
the usual manner. Such a device is explained in detail
in United States Patent No. 2,993,976 issued to Robert
L. Moore, and assigned to the assignee of the present
invention. In employing this device in the present in-
vention, the adjustable control 42 is provided with a
wattage control cycling element between the terminals
42e and 42d and a heater disconnecting switch between
the terminals 42c and 42a and a pilot light disconnecting
switch between the terminals 42c and 42b. The adjust-
able control 43 is likewise provided with a wattage con-
trol cycling element between the terminals 43e and 43d
and a heater disconnecting switch between the terminals
43c and 43a and a pilot light disconnecting switch be-
tween terminals 43c and 43b. A manually adjustable
switch 44 is located in the line L1 between the safety
interlock switch and the terminal 43d, and is movable
from a position connecting the line L1 to the terminal
43d, to the position shown, connecting the terminal 43d
to the cycling thermostat 41. A second line from the
thermostat 41 is connected to the ground line N to com-
plete the warming circuit.

With the circuit connected as shown, the surface units
22 and 23 are connected across the line L2 and the ground
line N through the cycling thermostat 41. When the con-
trols are turned to a setting which may be designated on
the control knob as "warming," the surface units 22 and
23 will heat the area above the shelf member 11, and
will be cycled on and off by the thermostat 41. The bi-
metallic element employed between the contacts 43d and
43e or 42d or 42e will remain closed during the heating
process, as they are designed to operate on 236 volts and
will not heat sufficiently to open on the 118 volt circuit.

In FIG. 7 there is shown an alternate circuit which
may be employed with the present invention. In the
circuit shown, the cycling thermostat 41 is disposed be-
tween the power source provided for L1 and the terminal
43d, as in the prior embodiment. However, the safety
interlock switch 24 has been omitted from the circuit
and the structure eliminated from the range construction.
With the surface units 22 and 23 removed from beneath
the shelf 11, and in the exposed position, the area adja-
cent the warming shelf remains cool and the cycling
thermostat 41 remains closed, thereby providing normal
operation of the adjustable controls 42 and 43. Should
the surface units 22 and 23 be inadvertently moved be-
neath the shelf 11, the heat generated by the surface units
causes operation of the cycling thermostat 41, and the
surface units operate as warming units for the warming
shelf producing insufficient heat to harm adjacent struc-
tures. It is, therefore, apparent that the thermostat 41
acts both as a temperature responsive element during the

warming process and as a safety device when used in the
circuit as shown.

In the embodiment shown, the warming shelf 11 has
been used in conjunction with an eye-level oven, and
provided with slidable doors 17 and 18, thereby providing
an oven enclosure above the shelf. It should be apparent,
however, that the shelf 11 may be used as a warming
medium without the closure members 17 and 18, or in a
structure provided solely for the warming of articles without
the eye-level oven.

While the invention has been shown in but one form, it
will be obvious to those skilled in the art that it is not
so limited, but is susceptible of various changes and
modifications without departing from the spirit thereof.

What is claimed is:

1. A domestic range comprising;
wall structure including a horizontal shelf member,
a pair of side walls, a top wall and rear wall defining an
oven enclosure,
a slidable member having a horizontal top surface
disposable below said shelf member,
a plurality of heating units provided on said surface,
said slidable member being movable from a first position
wherein one of said surface units is disposed be-
neath said oven enclosure to a second position wherein
in said unit is exposed for surface heating utensils,
and
means for transfer of heat energy from said one heating
unit to said oven enclosure,
whereby said heating unit is a source of heat energy
for said oven enclosure when in said first position
and a source of heat energy for heating of utensils
when in said second position, said heat transfer means
comprising the combination of
said slidable member having an opening located below
said top surface and near said one heating unit,
said wall structure defining a duct communicating with
said oven enclosure and said opening, to thereby
transfer heat energy to said oven enclosure by con-
vection.
2. The structure of claim 1 wherein said shelf member
comprises;
a pair of substantially parallel sheets,
and said heat transfer means further comprises the
combination of
a block of material having good heat conductivity dis-
posed between said plates and over said one heating
unit when said heating unit is in said first position
for transfer of heat from the lower side of said
shelf to said oven enclosure by conduction, and
said sheets each having a plurality of holes therein for
the transfer of heat from the lower side of said shelf
member into said oven enclosure by convection.
